UNITED STATES PATENT OFFICE.

STEPHAN BOHNERT, OF CLEVELAND, OHIO.

HINGE.

1,167,881.

Specification of Letters Patent. Patented Jan. 11, 1916.

Application filed October 27, 1915. Serial No. 58,153.

To all whom it may concern:

Be it known that I, STEPHAN BOHNERT, a subject of the Emperor of Austria-Hungary, residing at Cleveland, in the county of 5 Cuyahoga and State of Ohio, have invented certain new and useful Improvements in Hinges, of which the following is a specification.

This invention relates to hinges and particularly to hinges suitable for use with 10 table leaves and under other conditions where it is desirable to have a hinge which is flush with the surfaces to which it is applied, so that when opened the top will be 15 entirely flat, and which when closed will be concealed and will hold the surfaces out of contact with each other at the hinge connection.

A further object of the invention is to 20 provide an improved hinge of this type which will be strong and rigid, and easily assembled.

In the accompanying drawings—Figure 1 is a front elevation of part of a sewing machine table provided with the hinge. Fig. 2 is a perspective of a part of the hinge. Fig. 3 is an end view of the connecting members or links between the hinge leaves, in open position. Fig. 4 is a similar view of 30 the parts in closed position. Fig. 5 is a top plan of said parts. Fig. 6 is a top plan view of the hinge, open. Fig. 7 is a side view thereof, closed. Fig. 8 is a section on the line 8—8 of Fig. 6. Fig. 9 is a similar 35 view, with the hinge closed. Fig. 10 is a perspective of one of the hinge leaves.

Referring specifically to the drawings, 40 indicates the standing part or table top to which the swinging part or table leaf 7 is hinged.

The hinge comprises two similar leaves or plates 8, which are flat, and adapted to be set into the surfaces of the parts to be connected, and fastened by screws 9 through 45 holes 10, and preferably flush with the surfaces. Each leaf has at one end thereof a marginal tongue 11, bent over parallel to the leaf, on the inner side thereof, and adjacent each of these tongues is an eye 12 formed by bending another tongue to circular 50 form. A space 12' is produced between each pair of eyes 12, and receives the connecting links or members. A plurality of these links or members are employed, divided 55 into two sets, each set consisting of a number of plates 13 with convex outer edges

as indicated at 14 and with notched inner edges as shown at 15. These two sets of plates are connected in alternate or interleaved relation by means of a pivot pin 16, 60 so that they are free to work on or beside each other. The members of each set are also connected at one end by a pintle or pin 17 which projects into the eyes 12 of the hinge leaf, at each end, and when the hinge 65 is closed these pintles are received or swing into the notches 15 which are in alinement across each set. At the end opposite the pintle 17 the members of each set are connected by a pin 18, the ends of which are 70 flattened as indicated at 19, and these flattened ends are slidable or movable laterally in guides formed by the tongues 11 of the leaves. The members of the respective sets cross each other, and each set is connected 75 at one end by the pintle 17 to one leaf, and at the other end by the pin 18 to the other leaf.

When the hinge is opened, as shown in Fig. 3, the pins 18 and their flattened ends 80 19 slide outwardly in the guides under the tongues 11, until the parts 6 and 7 stop or abut against each other, at which time, also, the knuckles of the leaves 8 come together, and assist in supporting any weight on the 85 hinge. When the hinge is closed, as shown in Fig. 4, the pins 18 at first have a sliding movement inwardly under the tongues 11, incident to the different axes of movement on the pintles 17, the pivot 16 approaching 90 or being moved toward a line between said pintles, and on further closing movement the pins 18 again move or slide inwardly under the tongues 11 until the pintles 17 strike or stop against the inner ends of the 95 notches 15, as shown in Fig. 4. This action produces an extension or spreading of the leaves, so that they are opened up or lifted apart and do not contact with each other, whereby the table leaf 7 is held out of contact with the top 6, as shown in Fig. 9. The leaf and top are mortised as shown at 20 to receive the sets of connecting members on the inner or under sides of the hinge leaves.

The hinge is quite easily assembled, the 105 leaves being first produced, and the connecting members assembled therewith by placing the same in the recesses 12' and inserting the pintles 17.

What I claim is:

1. A hinge comprising two leaves, each leaf having a pair of eyes and a pair of

tongues bent to form guideways, sets of connecting members pivoted together and to the eyes of either leaf, and a pin extending through the members of each set and having flattened end portions slidable in said guideways.

2. A hinge comprising two leaves, each leaf having a pair of tongues bent inwardly at the ends of the leaves to form guideways, and sets of connecting links pivoted together and to either leaf and having projections slidable in said guideways.

3. A hinge comprising two leaf plates having eyes at their adjacent ends and also

tongues at said ends bent backwardly to 15 form guideways between said tongues and the plates, sets of connecting members pivoted together and to the eyes of either leaf, and pins connecting the members of each set and projecting at their ends into the 20 guideways.

In testimony whereof, I do affix my signature in presence of two witnesses.

STEPHAN BOHNERT.
